UNITED STATES PATENT OFFICE.

MAX MEDEKER, OF BLOEMFONTEIN, SOUTH AFRICA.

SANATORIUM.

Application filed September 28, 1926, Serial No. 138,294, and in Germany January 19, 1925.

The object of this invention is to provide a building of such construction that sick or disabled persons may obtain relief therein from climatic conditions and by sojourning 5 for a sufficient period recover their health. The invention seeks to provide a structure whereby all natural light will be excluded and high temperatures resulting from direct sunlight will be rendered harmless. The invention is illustrated in the accompanying drawings and will be hereinafter fully set forth.

In the drawings:

Figure 1 is a front elevation of a building embodying my invention;

Fig. 2 is a horizontal section on the line 2—2 of Fig. 1;

Fig. 3 is a vertical section on the line 3—3 of Fig. 2;

Fig. 4 is a detail section on the line 4—4 of Fig. 3, and

Figs. 5 and 6 are diagrammatic plan views of modifications.

In carrying out the invention, there is first 25 provided a foundation 7 of concrete or other permanent material which is carried a suitable distance above the ground level, as shown clearly in Figs. 1 and 3. Upon this foundation, there is erected an inner wall 24 30 which, in Figs. 1 and 3, defines a single rectangular room. A flat roof 24^a is carried by the wall 24, and this roof is preferably constructed of reinforced concrete, while the wall is of brick or other preferred material.

The inner wall 24 is spaced from the sides and ends of the foundation and around the said inner wall is erected an outer wall 4 which is spaced from the inner wall throughout its extent, as clearly shown in Fig. 2, and

40 this outer wall may be constructed with a wing 3 cooperating with an inner wing 16 to define an entrance lobby 1. The walls 3 and 16 are spaced apart and parallel, just the same as the walls 4 and 24, and at the front

45 of the building they are connected by walls 20 and 21 defining a hall 19, a door 6 being located in and normally extending across said hall. Cross walls 26 and 27 connect the walls 4 and 24 at the back of the lobby 1 to

50 define a hall connecting the lobby with the inner room 2, and in which is a door 5 normally extending thereacross. It will be seen that the space 17, between the walls 3 and 16, and the space 25, between the walls 4

55 and 24 are closed at the bottom and all vertical sides so that they provide heat insula-

tion for the structure. Through the outer wall at the juncture of the same with the foundation, I form openings 80 which are relatively small and extend in a horizontal series entirely around the building, louvers 8 being provided in the openings. Upon the entire area of the foundation which is bordered by the outer wall, I place bricks 10 in rows and in spaced relation to the wall and to each other, the bricks in adjacent rows being staggered and a central space being left clear, as indicated at 11. A reinforced concrete floor 13 is laid upon the bricks or blocks 10 so that there results a multiplicity of covered channels extending from the openings 80 to the spaces 11, under the lobby and the inner room 2 respectively. Set in the floor are gratings 14 and 15 through which the air is permitted to pass into the building.

Immediately below the roof 24^a, openings 280 are formed through the inner wall and louvers 28 are located in said openings, similar openings 90 equipped with louvers 9 being formed through the outer wall at the top thereof. It will be noted that the outer wall extends some distance above the inner wall and an outer roof 4^a of reinforced concrete is carried by the outer wall, an air space being thus formed over the entire inner roof. A gutter 4^b to carry off rain water is provided at the edges of the outer roof, and at the center of said roof is a draft flue 4^c whereby a positive vent is provided and the desired air circulation set up within the building. Baffles 4^d within the draft flue prevent choking thereof by birds without interfering with the outflow of foul air.

The two structures may, of course, be built of brick or reinforced concrete or other material which is sufficiently durable and weather-resisting and the walls will be of such thickness as to effectually resist the transmission of heat or cold so that an even comfortable temperature will be maintained within the inner structure.

Inasmuch as heated air naturally rises, there is generally a layer of cool air immediately at the ground surface in all localities and under all conditions. This air stratum will flow through the inlet openings 80 of the outer wall and circulate through the passages between the bricks or blocks 10 to the spaces 11 and gratings 14 and 15, and thence enter the rooms. The air will escape through the openings 280 and 90

and the flue 4°, and thus a constant circulation of air will be automatically established through the building so that the rooms will be thoroughly ventilated, but inasmuch as the structure is devoid of windows or other openings, except the minimum number of doors needed to afford access to the rooms, and a very substantial air space is provided by and between the inner and outer walls, the temperature in the rooms of the inner building will be even and maintained at such degree as may be desired to meet the needs of any patient. The several openings or passages providing for a circulation of air may be equipped with any approved form of cut-off devices or temperature measuring and controlling instrumentalities so that the desired temperature may be easily attained. The particular form or floor plan of the buildings may be varied at will but in all cases the walls and partitions should be sufficiently thick to be sound-proof and to prevent the transmission of heat so that a patient occupying any room will be assured of such quiet and freedom from disturbances as are conducive to recovery. The building may be advantageously utilized in all climates and is especially efficient in tropical climates.

In Figs. 1, 2 and 3, I have shown a building having a single room in addition to the lobby or office. In Fig. 5, there is shown an arrangement in which there is a room 31 at the rear of the lobby 29 and rooms 30 and 32 at the respective sides of the lobby. Inner walls 33 and outer walls 34 define an air space 35 surrounding each and all of the

rooms, and define narrow halls leading from the outside into the lobby and from the lobby to the several rooms. Doors 36, 37, 38 and 39 control the several halls. A grating 40 is located in the floor of each room at the center thereof.

In Fig. 6, the lobby 41 is located at one end of a long corridor 42 and rooms 44 are located along both sides of the corridor, separate doors 43 controlling the entrance to the rooms. Entrance to the lobby is had through a door 45 and a door 46 controls the passage from the lobby to the corridor. A grating 47 is provided at the center of each room.

Having thus described the invention, I claim:

A structure for the purpose set forth comprising an outer building having air inlet openings through its wall immediately adjacent the bottom thereof, and air outlet openings through its wall immediately adjacent the roof, an inner building spaced throughout from the outer building and containing rooms, the wall of the inner building being provided with outlet openings immediately adjacent its roof, a floor common to the two buildings having openings therethrough into the centers of the respective rooms in the inner building, and elements below the floor defining passages leading from the air inlets of the outer building to said openings in the floor.

In testimony whereof I affix my signature.

MAX MEDERER. [L.S.]
